UNITED STATES PATENT OFFICE.

BENJAMIN B. LINSKIE, OF DALLAS, TEXAS.

SEWER-CLEAN-OUT COVER.

1,073,150.

Specification of Letters Patent. Patented Sept. 16, 1913.

Application filed March 15, 1912. Serial No. 684,052.

To all whom it may concern:

Be it known that I, BENJAMIN B. LINSKIE, a citizen of the United States, residing at Dallas, in the county of Dallas and State of Texas, have invented certain new and useful Improvements in Sewer-Clean-Out Covers, of which the following is a specification.

My invention relates to new and useful improvements in sewer clean out covers, 10 and its object is to provide a cover for the clean out pipes of sewers, which cover will be securely held in place under ordinary circumstances and cannot be removed except by authorized parties carrying a certain 15 form of key, adapted to release the fastening mechanism.

A further object of the invention is to provide a device of the character described that will embody an inexpensive and simple 20 construction and that will be correlated with a fastening means, but may be released without difficulty by a person provided with the proper key.

With these objects in view, my invention 25 has relation to certain novel features of the construction and operation, an example of which is described in the following specification and illustrated in the accompanying drawing, wherein:

30 Figure 1 is a plan view of a sewer pipe clean out provided with the herein described cover, the pipe being shown embedded in the earth in the usual manner. Fig. 2 is a transverse, vertical, sectional elevation taken 35 upon the line A—A of Fig. 1. Fig. 3 is an underside view of the cover. Fig. 4 is a transverse, vertical, sectional elevation, showing the outlet end of the clean out casing, the cover being removed therefrom. 40 The section in this case is taken upon the line B—B of Fig. 1. Fig. 5 is plan view showing the outlet of the sewer clean out casing, the cover thereof being removed. Fig. 6 is a perspective detail view of the key 45 by which the lock or fastening means of the cover may be released.

Referring now more particularly to the drawings wherein like numerals of reference 50 designate similar parts in all figures, the numeral 1 denotes a metal casing adapted to be embedded in the ground and to communicate at its lower end with a sewer, the upper end of said casing being provided with an aperture flush with the level of the street 55 or road beneath which the sewer runs. A collar 2 formed integral with the casing 1

encircles the aperture in the top of said casing. The interior surface of the collar 2 is provided with a flange 3 forming a seat for the circular cover 4, which may be given 60 any of the many designs in common use. At one point a break is provided in the seat 3, as indicated at 5, the aperture forming said break being extended slightly into the collar 2. At a point removed substantially 65 90 degrees from the opening 5 a channel 6 substantially vertical is provided in the interior surface of the collar 2. Upon the under surface of the cover 4 adjacent to the edge thereof, a pair of apertured lugs 7 are 70 provided between which lugs a hook member 8 is pivoted. The upper edge of the hook member 8 is provided with a transverse slot 9, which slot is adapted to engage a lip 10 projecting slightly downward from the seat 75 3 adjacent to said hook. When the hook is in a substantially horizontal position, as shown in dotted lines in Fig. 2, lip 10 is disengaged from the slot 9, and the cover may be raised.

80 In order to prevent any possibility of the cover being removed by first raising a point thereof diametrically opposite to the hook, a curved finger 11 is integrally provided upon the under surface of the cover at the 85 point specified, and the extremity of said finger is made to project beneath the outstanding flange formed by the seat 3. Owing to this construction, the cover 4 can be removed only by first raising that portion 90 of its edge beneath which the hook 8 is mounted. In order to free the hook 8 from engaging with the lip 10 and raise it from the position which it normally occupies, due to its own weight, a key 13 is employed having 95 a pronounced bend at its middle portion and provided at one extremity with a hook 14. This key is adapted to conform to the slot 5 formed between the cover and the neck portion of casing. By passing the hook 100 end of said key through the slot 5, the hook member 8 may be engaged by the hook 14, and the hook may thus be drawn to the position indicated in dotted lines in Fig. 2. By then exerting a downward pressure upon 105 the upper end of the key, the middle portion thereof is made to form a fulcrum, resting upon the outer edge of the slot 5, and the key acts as a lever to raise the hook supporting edge of the cover. In order to guide the 110 key 13 in the proper direction when it is passed through the slot 5, a pair of lugs 15

are extended downwardly from the under surface of the cover at a point adjacent to said slot. The space between these lugs is sufficient to permit the key to pass between them and they serve to guide it in the proper direction to permit the hook 14 to grasp the hook member 8. A rib 16 is extended between the two lugs to reinforce the same and decrease the possibility of their being broken off. The channel 6 is provided in order to permit a chisel or some other form of lever to be driven in between the cover and its seat, in order to pry the cover loose in case it becomes rusted or frozen into place.

15 The invention is presented as including all such changes and modifications as come within the scope of the following claim:

What I claim is:

20 The combination with a sewer clean out casing having a key receiving recess, of a

circular cover fitting in the casing, a pair of spaced guide projections on the under-side of the cover in position adjacent the recess of the casing to receive a key inserted through the recess, a flanged projection on 25 the wall of the casing positioned diametrically opposite the guide projections, and a hook pivoted on the underside of the cover diametrically opposite to the guide projections and normally engaging the flanged 30 projection of the casing, said hook having a depending key receiving portion.

In testimony whereof I have signed my name to this specification in the presence of two subscribing witnesses.

BENJAMIN B. LINSKIE.
